ATTORNEY.

UNITED STATES PATENT OFFICE.

VICTOR A. LILLQUIST, OF SUPERIOR, WISCONSIN.

WRENCH.

1,352,009.

Specification of Letters Patent.

Patented Sept. 7, 1920.

Application filed November 17, 1919. Serial No. 338,602.

To all whom it may concern:

Be it known that I, VICTOR A. LILLQUIST, a subject of Finland, residing at Superior, in the county of Douglas and State of Wisconsin, have invented certain new and useful Improvements in Wrenches, of which the following is a specification, reference being had therein to the accompanying drawing.

10 This invention relates to wrenches and has special reference to an automatically closing wrench. The principal object is to provide a more convenient, durable and practical wrench than heretofore known.

15 Other objects and advantages of the peculiar structure will appear in the further description of the invention.

In the accompanying drawings forming part of this application and in which like reference character indicate like parts:

20 Figure 1 is a side elevation of one of my assembled wrenches with the near half of the handle housing removed.

Fig. 2 is a perspective view of a pipe 25 gripping jaw adaptable to the wrench.

Fig. 3 is a transverse sectional view on the line 3—3, Fig. 1, and

Fig. 4 is a transverse sectional view on the line 4—4, Fig. 1.

30 The main body portion of the wrench comprises a shank 1 and handle 2, the former being substantially I-shaped in cross section and the handle is a continuation of same except that the central portion thereof 35 is cut out, forming an elongated slot 3, the inner end wall 4 of which is of the same width as the lower cross bar 5 of the I of the shank, the opposite end 6 of the handle being the same thickness.

40 A suitably shaped jaw 7 is formed integral with the shank 1 and a somewhat similarly shaped movable jaw 8 though longer than the jaw 7 is slidably mounted against the inner face of the shank 1 and has integrally formed therewith a shank 9 extending longitudinally the lower edge of the other shank and handle.

The jaw 8 has upwardly and inwardly extending rectangularly shaped opposed engaging members 10 which slidably operate within the channels formed in the sides of the shank 1. A portion indicated at 11 of the cross bar 5 in the shank and adjacent the end wall 4 of the slot 3 is cut away upon 55 both sides flush with the face of the bottom of the channels, this being for the purpose

of permitting application and removal of the engaging members 10 when desired.

An expansive spiral spring 12 is mounted in the angle formed at the outer termination of the handle, the office of which is to normally hold the dog 13 with its notched face engaging the notches 14 in the shank 9 of the jaw 8, the handle end 15 of the dog adjacent its engagement with the spring 60 being conveniently shaped for engagement by preferably the little finger of the operator's hand.

A second expansive spiral spring 16 is mounted intermediate of the end of the 70 shank 9 and the side of the spring 12 the office of which spring is to normally maintain the jaw 8 in its farthermost extended or closed position in relation to the fixed jaw, thus when the dog 13 is released from 75 engagement with the teeth of the shank the spring 16 will automatically force the latter outwardly, it being of the proper tension not to actuate the shank 9 so long as the dog 13 is in normal engagement therewith.

80 One side wall of the handle housing is indicated at 17 the other being identical in shape except that it has no angular extension and is omitted for convenience of illustration. These side walls are both formed 85 with concavo-convex channels indicated at 18 extending longitudinally thereof and forming suitable side walls in the spring tunnel or channel to prevent the spring 16 from buckling or getting out of position.

I prefer to form integral with the side wall 17 the lower edge wall 19 of the handle, having suitable enlargements for the through rivets indicated at 20 by which the side walls are firmly united to the handle 95 of the wrench,—and which also hold the pivotal support 21 of the dog 13.

I have shown at 22 a triangularly shaped serrated movable jaw having opposed holding straps 23—23 rigidly fixed thereto and 100 which straps carry slight protrusions 24 upon the inner free ends thereof and which protrusions register with suitable recesses indicated at 25 on the sides of the jaw 8 of the wrench so that when desired the jaw 105 22 may be sprung into position upon the jaw 8 and frictionally carried thereby when it is desired to use the wrench for operation upon a pipe or other cylindrical object.

In operation and after assemblage, the 110 wrench is used ordinarily with one hand it being evident that by pressing inwardly of

the handle end of the dog 13 the shank 9 is released and the spring 16 will expansively contract the jaws 7 and 8 upon any object desired and by releasing pressure 5 upon the handle of the dog the wrench will be so locked for turning action. To again open the jaws all that is necessary is to depress the handle of the dog 13 and push forwardly and longitudinally the wrench 10 which will force the slidable jaw with its shank 9 backward and when the pressure is released again upon the dog handle the jaws will remain in such spaced position as before described.

15 Attention is again directed to the jaw 8 being longer than the jaw 7 which is for convenience in applying the wrench to the nut or bolt in an inaccessible position; and when it is not convenient to open the jaws 20 of the wrench in any other way the latter may be placed with the projection of the jaw 8 against the side of the nut or any other convenient object, and by pushing forward of the wrench the jaws may be readily 25 separated to any distance desired, as is obvious.

Having thus described my invention what I claim and desire to secure by Letters Patent is:

30 1. The combination with a wrench of the character described including a main shank having opposed rectangularly shaped channels in its sides and a fixed jaw on the forward end thereof, a spring actuated shank carrying a jaw and slidably engaged with the main shank having two opposed integrally formed engaging members thereupon which co-operatively engage with the channels in the main shank, said slidable

shank having teeth adjacent the opposite 40 end thereof, a spring for actuating the slideable shank, and a toothed spring actuated lever for holding said shank in any predetermined position and a two part separable handle portion, there being cut away portions in the main shank whereby when the slideable shank is in its farthest open position and the handle portions separated the shanks may be removed from engagement with each other.

50 2. The combination with a wrench of the character described including a main shank with a fixed working jaw at one end and an L-shaped termination at the other end, a slideable shank carrying a working jaw for 55 co-operative action with the other working jaw, and having teeth formed in the lower end thereof, a two part handle, and an expansive spiral spring intermediate of the end of the slideable shank and the L-shaped 60 termination of the main shank, of a pivoted toothed lever intermediate of the two parts of the handle, engaging the toothed portion of the slideable shank for holding it in any predetermined position and an expansive 65 spiral spring intermediate of the end of the first mentioned spiral spring and the L-shaped termination of the main shank, engaging the operative end of the lever and holding it normally extended adjacent said 70 L-shaped extension.

In testimony whereof I hereunto affix my signature in the presence of two witnesses.

VICTOR A. LILLQUIST.
